US00D801644S

(12) **United States Design Patent** (10) **Patent No.:** **US D801,644 S**
(45) **Date of Patent:** **** Nov. 7, 2017**

(54) **CAP WITH RECTANGULAR-SHAPED ELECTRONIC DISPLAY SCREEN**

(71) Applicant: **Andrew Zenoff**, San Anselmo, CA (US)

(72) Inventor: **Andrew Zenoff**, San Anselmo, CA (US)

(73) Assignee: **Beam Authentic, LLC**, San Anselmo, CA (US)

(**) Term: **14 Years**

(21) Appl. No.: **29/499,861**

(22) Filed: **Aug. 19, 2014**

(51) LOC (10) Cl. **02-03**

(52) U.S. Cl.

USPC **D2/882**

(58) **Field of Classification Search**

(57) **CLAIM**

The ornamental design for a cap with rectangular-shaped electronic display screen, as shown.

DESCRIPTION

FIG. 1 is a perspective view of a cap with rectangular-shaped electronic display screen;
FIG. 2 is a front elevation view of the cap with rectangular-shaped electronic display screen;
FIG. 3 is a side elevation view of the cap with rectangular-shaped electronic display screen; and,
FIG. 4 is a top plan view of the cap with rectangular-shaped electronic display screen as shown.

1 Claim, 2 Drawing Sheets
